United States Patent Office

Des. 215,820
Patented Nov. 4, 1969

215,820

BOTTLE

Robert J. Donoghue, 900 Windsor Ave.,
Windsor, Conn. 06095

Filed Nov. 1, 1968, Ser. No. 14,276

Term of patent 14 years

Int. Cl. D9—01
U.S. Cl. D9—119

FIG. 1

FIG. 3

FIG. 2

FIG. 4

FIG. 1 is a top plan view of a bottle embodying my new design,

FIG. 2 is a front elevational view thereof;

FIG. 3 is a cross-sectional view taken on the line 3—3 of FIG. 2; and

FIG. 4 is a fragmentary cross-sectional view taken on the line 4—4 of FIG. 2.

I claim:

The ornamental design for a bottle, substantially as shown and described.
